WRENCH

Oscar Becklin, Los Angeles, Calif.

Application June 23, 1937, Serial No. 149,907

2 Claims. (Cl. 81—91)

This invention relates to a tool of the wrench type and relates more particularly to a wrench for gripping and turning pipe and other objects such as bolts, nuts, etc. A general object of this 5 invention is to provide a practical, effective wrench that is particularly easy and convenient to manipulate.

Another object of this invention is to provide a wrench that is adapted to obtain a firm, dependable grip on a pipe or other object without the manual manipulation of a nut, screw or the like.

Another object of this invention is to provide a wrench of the character mentioned that is 15 operable to obtain a gripping engagement with a pipe or other object that is increased in intensity in proportion to the turning force imposed on the wrench handle.

Another object of this invention is to provide 20 a wrench that is operable to dependably and securely grip objects varying considerably in size and to obtain a secure engagement with all objects within its range of adjustment.

Another object of this invention is to provide 25 a wrench of the character mentioned embodying a novel, simple spring means for automatically urging the wrench jaws into initial engagement with the object to be gripped or turned.

Another object of this invention is to provide 30 a wrench of the character mentioned embodying two pivotally connected jaws pivotally associated with the wrench handle in such a manner that a substantial leverage or mechanical advantage is obtained to force the jaws into engagement with the object being gripped or turned 35 when a turning force is applied to the handle.

A further object of this invention is to provide 40 a wrench embodying a handle shaped in such a manner that a very heavy force may be applied to it without bruising or injuring the hands.

The various objects and features of my invention will be fully understood from the following 45 detailed description of typical preferred forms and applications of my invention, throughout which description reference is made to the accompanying drawing, in which:

Fig. 1 is a side elevation of a wrench of the present invention with its jaws in engagement with a pipe or similar object. Fig. 2 is a side 50 elevation of the outer portion or principal portion of the wrench showing the jaws in the collapsed or retracted positions. Fig. 3 is a transverse detailed sectional view taken as indicated by line 3—3 on Fig. 1. Fig. 4 is a transverse sectional view taken as indicated by line 4—4 on

Fig. 1, and Fig. 5 is a fragmentary side elevation of a slightly modified form of the invention intended primarily for engaging polygonal objects such as bolt heads, nuts, etc.

The improved wrench of the present invention illustrated in Figs. 1 to 4, inclusive, of the drawing, includes, generally, a handle 10, an inner jaw 11 pivoted to the handle 10, an outer jaw 12 pivoted to the inner jaw 11 and pivotally and shiftably connected with the handle 10, and spring means 13 urging the jaws 11 and 12 toward one another.

The handle 10 is an elongate lever-like part adapted to be grasped and held by the workman or user of the tool. The handle 10 is preferably an elongate integral member of substantial length. In accordance with the invention the handle 10 is substantially T-shaped or I-shaped in transverse cross section, having a bead or flange 14 extending along its rear edge and a 20 bead or flange 15 extending along its forward edge. The flange 14 at the rear edge of the handle 10 relative to the direction of turning of the handle as indicated by the arrow A in Fig. 1 is comparatively wide to present a broad surface 25 16 to be engaged and pressed against by the palm and heel of the user's hand. The flange 15 is preferably somewhat narrower than the flange 14. The surfaces of the handle flanges 14 and 15 may be smooth and rounded. The 30 handle 10 shaped as just described is particularly convenient to grasp and use and its broad flange 14 greatly facilitates the employment of the wrench, particularly where a heavy turning force is applied to the handle 10.

The handle 10 is provided at its active end or inner end with a lug or lever 17. The lever 17 is integral with the handle 10 and is preferably somewhat narrower than the handle. In the preferred construction the lever 17 has flat parallel sides. In accordance with the invention the lever 17 is pitched relative to the handle 10, that is, the longitudinal axis of the lever 17 is angularly related to the longitudinal axis of the handle 10. The longitudinal axis of the lever 17 extends outwardly and rearwardly relative to the longitudinal axis of the handle 10, as clearly illustrated in Figs. 1 and 2 of the drawing.

The inner jaw 11 is one of the pipe or object engaging elements of the tool and is pivotally associated with the handle 10. The jaw 11 is an elongate member provided with a convex active end 18 for cooperating with the pipe or object O. In the form of the invention being described the active end 18 of the jaw 11 has a series of grip-

ping teeth 19. The teeth 19 are preferably V-shaped in cross section and extend transversely across the jaw end 18. The jaw 11 is preferably somewhat wider or thicker than the handle 10 and has flat parallel side surfaces. The jaw 11 is provided adjacent its active end with a laterally or rearwardly projecting lug 20. The lug 20 is thinner or narrower than the jaw 11 and preferably has flat parallel sides. The jaw 11 is provided at its outer or other end with a laterally or rearwardly projecting lug 21. The lug 21 is bifurcated or yoked and the lever 17 is received in its outer or rear portion. A pivot pin 22 is passed through an opening in the lever 17 and is received in openings in the lug 21 to pivotally connect the jaw 11 with the lever 17. The heads of the pin 22 are preferably flush with the side surfaces of the lug 21. The point of pivotal connection of the jaw 11 with the lever 17 is adjacent the handle 10. It is a feature of the invention that the axis of pivotal connection of the jaw 11 with the lever 17 is only slightly off-set from the longitudinal axis of the handle 10 and that the toothed outer end 18 of the jaw 11 is transverse of and intersected by the longitudinal axis of the handle 10 when the jaws 11 and 12 are in active engagement with the pipe or object O. This will be apparent from an inspection of Fig. 1 of the drawing where the broken line X 30 designates the longitudinal axis of the handle 10.

The outer jaw 12 is the outer pipe engaging or object engaging element of the wrench and is pivotally supported on the jaw 11 and actuated by the lever 17 of the handle 10. The jaw 12 is a 35 generally L-shaped member having an outer arm 23 spaced from and opposing the toothed end 18 of the jaw 11 and a somewhat longer arm 24 extending inwardly or toward the handle 10. The arms 23 and 24 are at substantially right 40 angles to one another. The active inner side 25 of the jaw arm 23 is provided with teeth 26 opposing the teeth 19 of the jaw 11 and adapted to cooperate with the pipe or object O. It is to be particularly noted that the toothed inner side 25 of the jaw arm 23 is transverse of and intersected by the longitudinal axis X of the handle 10 and that the axis X is diametric of or substantially diametric of the pipe or object O engaged between the jaws 10 and 11. These relationships 45 are clearly illustrated in Fig. 1 of the drawing. The outer side or end of the arm 23 of the jaw 12 is preferably rounded. A flat inclined face 27 is provided at the inner end of the active face 25 of the jaw 12 to assist in gripping the object 50 O and to cooperate with the side surface of a polygonal object such as a nut, bolt head, or the like.

The arm 24 of the L-shaped jaw 12 is bifurcated or provided with a longitudinally extending slot 28. The slot 28 receives the lug 20 and the outer end portion of the lever 17. A pivot pin 29 is carried in openings in the bifurcated arm 24 and passes through an opening in the lug 20 to pivotally connect the jaw 12 with the jaw 11. The heads of the pin 29 are preferably flush with the side surfaces of the jaw arm 24. When the jaws 11 and 12 are collapsed or in the positions illustrated in Fig. 2 of the drawing, the axis of the pivot pin 29 is substantially aligned 60 with the longitudinal axis X of the handle 10. Upon opening of the jaws 11 and 12 the axis of the pin 29 moves rearwardly to a position such as illustrated in Fig. 1 of the drawing.

In accordance with the invention the outer 75 jaw 12 has a shiftable and pivotal connection

with the lever 17 of the handle 10 whereby the jaw 12 is actuated by the lever when a force is applied to the handle in the direction indicated by the arrow A. A slot 30 is provided in the end portion of the lever 17 remote from the handle 10. The slot 30 is elongate and has its major axis pitched or inclined with respect to the lever 17 being substantially parallel with the longitudinal axis of the handle 10. In accordance with the invention the slot 30 is spaced a considerable distance from the pin 22 pivotally connecting the jaw 11 with the lever 17. A pin 31 is carried by the end portion of the jaw arm 24 and passes through the slot 30. The heads of the pin 31 are preferably flush with the side surfaces of the jaw arm 24. The pin 31 is shiftable in the slot 30 to permit pivotal movement of the jaw 12 relative to the jaw 11 and is engaged or acted on by the wall of the slot 30 for the transmission of the turning force from the lever 17 to the arm 24 of the outer jaw 12. It is to be observed that the point of pivotal connection between the lever 17 and the jaw arm 24 is spaced between the pivot pins 22 and 29 so that the lever 17, the inner jaw 11 and the arm 24 of the outer jaw 12 form a toggle assembly. When the handle 10 is swung or turned in the direction indicated by the arrow A the pin 31 cooperates with the wall of the slot 30 to pivot the jaw 12 relative to the jaw 11 to bring the teeth 26 into tight engagement with the object O. Simultaneously with the pivoting of the jaw 12 the jaw 11 has some pivotal movement on the pin 22 and swings with the handle 10. The operation of the jaws 11 and 12 will be more fully 35 described.

The means 13 is provided to yieldingly hold the jaws 11 and 12 in their collapsed or inoperative positions illustrated in Fig. 2 of the drawing and to urge the jaws 11 and 12 into initial cooperation with the object O when the jaws are arranged on the object. The means 13 is automatic and is in the nature of a spring means. The means 13 comprises a spring 32 secured to the handle 10 and acting on the jaw 11. The spring 32 is preferably a leaf spring and has one end fixed to the handle 10 adjacent the lever 17 by rivets 33 or the like. The spring 32 extends outwardly between the forks or arms of the bifurcated lug 21 and its free end or outer end bears on the rear edge of the jaw 11. The spring 32 bearing on the jaw 11 tends to pivot the jaw 11 relative to the handle 10 and the jaw 11 being pivotally connected to the jaw 12 in turn tends to swing or pivot the jaw 12, the two jaws being normally or initially held in the positions illustrated in Fig. 2. It is to be noted that the spring 32 is substantially entirely received in the bifurcated lug 21 and is disposed at the rear edge of the jaw 11 where it is fully protected and where it does not interfere with the free use of the tool. The forward edge 34 of the inner jaw 11 forms a surface that may be conveniently pressed against by the thumb of the user's hand grasping the handle 10 to pivot the jaw 11 rearwardly for the purpose of opening the wrench. The wrench may be easily opened by engaging the jaw 12 on the object O to be gripped or turned and then exerting a force on the handle 10 which causes the jaws 11 and 12 to pivot or 50 open for the reception of the object.

Fig. 5 of the drawing illustrates a slightly modified form of the invention intended primarily for engaging and turning polygonal objects such as bolt heads, nuts, etc. In this form of 75

the invention the active end 18^a of the jaw 11 is smooth or devoid of teeth and the inner side or active side 25^a of the jaw arm 23 is flat and devoid of teeth. As illustrated in Fig. 5 of the drawing the side 25^a and the surface 27 are adapted to flatly bear against or engage adjacent faces of a polygonal nut N or the like, while the active end 18^a of the jaw 11 is adapted to engage against an opposite side or corner of the nut. The wrench illustrated in Fig. 5 of the drawing may be the same as the above described form of the invention in other respects.

It is believed that the operation of the wrench provided by this invention will be readily understood from the foregoing detailed description. As described above, the jaws 11 may be readily opened by pressing against the forward edge 34 of the jaw 11 or by engaging the arm 23 of the jaw 12 with the object and then exerting a force on the handle 10 to spread the jaws to receive the object O. The spring 32 tends to swing the jaws 11 and 12 together and when the object O is received between the jaws the spring 32 urges the jaws into initial engagement with the object. A turning force may then be exerted on the handle 10 in the direction indicated by the arrow A to actuate the jaws 11 and 12 into tight, firm engagement with the object O and to turn the object or to resist turning of the object, as the case may be.

The force exerted on the handle 10 is transmitted to the jaw 11 by the pin 22 and urges the teeth 19 of the jaw into firm engagement with the object O. The turning force exerted on the handle 10 also tends to swing the lever 17 rearwardly and the pin 31 cooperates with the wall of the slot 30 to swing the outer end of the jaw arm 24 rearwardly. The force transmitted to the jaw 12 by the pin 31 cooperating with the wall of the slot 30 pivots or tends to pivot the jaw 12 to force its teeth 26 into firm dependable engagement with the object O. Thus the turning force exerted on the handle 10 actuates both jaws 11 and 12 into tight engagement with the object O. The pivotal axes of the jaws 11 and 12 and the slot 30 are related so that a substantial leverage or mechanical advantage is obtained when the jaws 11 and 12 are actuated, as just described. The slot 30 is of sufficient length to permit the wrench to handle or grip objects varying considerably in size and the slot is related to the lever 17, the jaw arm 24 and the pivot pins 22 and 29 so that the wrench is effective in firmly gripping the objects throughout its entire range of adjustment, or operation. The jaws 11 and 12 may be readily released from the object O by exerting a force on the handle 10 in the direction opposite to that indicated by the arrow A or by applying pressure to the edge 34 of the jaw 11 or both. The wrench of the present invention is small and compact and is simple and inexpensive to manufacture.

Having described only typical preferred forms and applications of my invention I do not wish to be limited or restricted to the specific details herein set forth, but wish to reserve to myself any variations or modifications that may appear to those skilled in the art or fall within the scope of the following claims.

Having described my invention, I claim:

1. A wrench comprising, an elongate handle, a lever on the inner end of the handle inclined rearwardly and outwardly relative to the longitudinal axis of the handle, an inner jaw arranged at the forward side of the lever, an active object engaging face on the inner jaw, a bifurcated lug projecting rearwardly from the inner jaw and receiving the lever, a pin pivotally connecting the lug with the lever adjacent the end of the handle and rearwardly of the longitudinal axis of the handle, the said active face of the inner jaw being substantially curved about the pivotal axis of the inner jaw, a substantially L-shaped outer jaw having a short arm spaced from and opposing the said active face of the inner jaw and having a long arm at the rear of the inner jaw, angularly related faces on the inner sides of the arms for engaging adjacent surfaces of a polygonal object, means pivotally connecting the intermediate portion of said long arm with the inner jaw at a point spaced outwardly beyond the lever, the lever having a slot spaced outwardly and rearwardly from said pin, and a pin on said long arm of the outer jaw cooperating with the slot.

2. A wrench comprising an elongate handle, an inner jaw pivotally connected with the outer end part of the handle at a point rearwardly of the longitudinal axis of the handle, the inner jaw having an outwardly facing gripping face curved substantially concentric with the pivotal axis of the inner jaw, an outer jaw pivotally connected with the inner jaw at a point spaced outwardly and rearwardly from the point of connection of the inner jaw with the handle and having a gripping face opposing the gripping face of the inner jaw, a pin and slot connection between the handle and the outer jaw spaced between the point of connection of the inner jaw with the handle and the pivotal connection between the jaws and providing for pivoting and shifting of the outer jaw relative to the handle, said gripping faces and the connections between the jaws and handle and the pin and slot connection being related so that said faces are substantially normal to and are intersected by the longitudinal axis of the handle when the jaws are gripping an object and are at an acute angle to and spaced from the said axis when the jaws are inactive, and spring means acting on one of the jaws to urge the jaws into initial gripping engagement with the object.

OSCAR BECKLIN.
